VAPOR GENERATOR

William T. Moore, Elmhurst, Ill., assignor to The Babcock & Wilcox Company, New York, N. Y., a corporation of New Jersey

Application June 2, 1949, Serial No. 96,731

5 Claims. (Cl. 122—333)

1
This invention relates to fluid heat exchange apparatus in which a vapor generator such as a water-tube type of steam generator is utilized to absorb heat from a gaseous medium at a high temperature (i. e., 2000—2600° F.) and under substantial pressure (i. e., 250—350 p. s. i.).

The invention involves an exterior pressure vessel of sufficiently large dimensions (i. e., height 50—100 feet, diameter 10—20 feet) to house the gas generator or furnace component and the tubular pressure part components of a vapor (or elastic fluid such as steam) generator with provisions for the necessary circulation of the internal and external heat exchange fluids involved.

As an example of the use of the invention, it may be employed in chemical processes in which the exterior pressure vessel constitutes a shell through which gaseous reactants or reactance products pass at temperatures of the order of 2500° F. and pressures of the order of 300 p. s. i. For example, oxygen, natural gas, or methane may be supplied to the shell as reactants, and the high temperature products of their reaction are then passed over the heat exchange parts of a vapor generator. The vapor or steam generator is employed, in such a process, to control the temperature of the gaseous products. In some processes it is important that the gaseous reactance products be reduced from a temperature of the order of 2500° F. to a temperature of the order of 600° F. This illustrates one of the results accomplished by the invention, and the pertinent operation may be controlled as to temperature by variation of the supply to the shell of one or more of the reactants. The steam or vapor generator may operate at a desired pressure within the range of 500—1700 p. s. i.

According to the invention, the heat exchange equipment constituting the vapor generator is arranged within the shell, to minimize costs, simplify the piping requirements, and render the overall process more effective. By this arrangement, provisions which must be made for differential movements of the pressure parts and the shell are minimized, and there is less pressure drop in the gases passing through the shell. The vapor generating system within the shell involves a bank of upright tubes having their upper ends rigidly connected to a liquid and vapor drum and their lower ends to a liquid drum, the bank of tubes and drum arrangement constituting an assembly which is supported by the shell at a position adjacent the upper drum.

In a preferred embodiment of the invention, the vapor or steam produced is conducted from

2
the upper part of the upper drum to a radiant superheater which includes a circular series of upright tubes arranged around the interior surface of the shell and functioning as shell wall cooling tubes to protect the shell against overheating.

In one process in which the invention is employed, natural gas is burned with a deficiency of oxygen in a combustion chamber (or reaction chamber) disposed in the shell but below the vapor generator. These gases react to develop gaseous products which pass upwardly from the combustion chamber and are caused to recurrently pass back and forth transversely of the bank or banks of vapor generating tubes before they leave the shell at its upper part. The natural gas and the oxygen react under pressures of the order of 300 p. s. i. and are effective in creating gaseous products within the temperature range of 2000—2500° F.

The apparatus of the invention is illustrated by an embodiment which is disclosed in the accompanying drawings in which:

Fig. 1 is a vertical section on the line 1—1 of Fig. 4;

Fig. 2 is a multiple plane vertical section on the section line 2—2 of Fig. 4;

Fig. 3 is a horizontal section on the line 3—3 of Fig. 1;

Fig. 4 is a horizontal section on the line 4—4 of Fig. 1;

Fig. 5 is a fragmentary view of Fig. 4 on an enlarged scale;

Fig. 6 is a view in the nature of a vertical section on the line 6—6 of Fig. 3, particularly showing the manner in which the upper drum of the vapor generator is supported within the shell;

Fig. 7 is a partial elevation showing two adjoining superheater tubes and the manner in which they are secured to the shell;

Fig. 8 is a partial horizontal section on line 8—8 of Fig. 7;

Fig. 9 is a partial horizontal section on the line 9—9 of Fig. 1, showing a full stud tube construction employed in a furnace zone of high temperature; and

Fig. 10 is a partial horizontal section on a line 10—10 of Fig. 1, showing a partial stud tube wall construction for a reaction zone of lower temperature.

The shell 10 is a welded steel pressure vessel which may have a diameter of from 10 to 20 feet and a height of 50 to 100 feet. It is fabricated to withstand internal fluid pressures considerably in excess of 300 p. s. i., and it is provided with gas

inlets at its lower portion and a gas outlet such as 12 at its upper part.

Within the lower part of the shell 10 is a combustion chamber or reaction chamber, 14 with thick refractory walls through which there are gas inlet ports such as 16 and 18, these ports also extending through the shell 10 as indicated in Fig. 1. In its upper part, the combustion chamber is provided with outlet ports such as 20 and 22, acting as a part of means directing high temperature gases over the heat exchange parts of the vapor generator.

The vapor or steam generator within the shell 10 includes a transverse upper drum 24 connected by banks 26 and 28 of steam generating tubes to a lower drum 30. The tubes are expanded into tube seats in the drums in a manner well-known in the art to form pressure tight connections, and the entire unit is suspended within the shell by means including an arrangement of elements such as that particularly indicated in Fig. 6. This arrangement involves a roller supporting bracket 32 secured to the wall of the shell 10, and an upper bracket 34 secured to the drum 24 and resting upon a roller 36, which, in turn, is supported by the bracket 32. There is a similar arrangement of drum supporting elements at each side of the shell, as indicated in Fig. 2.

The banks of vapor generating tubes 26 and 28 are separated by a diametrically disposed wall 37 (see Fig. 4) which includes the large diameter upright downcomer tubes such as 40-43. The spaces between these downcomer tubes are closed by means shown as refractory material to complete the wall in the form indicated in Fig. 4. These downcomers, being straight tubes and of greater structural strength than the smaller diameter tubes of the banks 26 and 28, provide a major part of the support necessary for the lower drum 30. One of the downcomer tubes, the tube 45, has a blow-down tube 50 extending therethrough from the lower part of the lower drum 30 to a position within the upper drum, indicated at 52 in Fig. 2. From this position, the blow-down tube extends laterally through the drum and shell walls to a blow-down valve (not shown). The lateral extension of the blow-down tube is indicated at 54 (Fig. 3). It is provided with thermal sleeve constructions 53 and 55 similar to that indicated at 174 for the feed water connection 170. The latter act as a part of means for supplying the vapor generator with a liquid for circulation therethrough. Tubular connections 57 and 59 for a gauge glass 61 have similar thermal sleeve constructions 63 and 65.

The lower part of the lower drum 30 is protected from the higher temperature gases adjacent the combustion chamber 14 by a refractory covering 54 which may be held in position on the lower part of the drum wall by metallic projections welded to the drum. This covering also extends over a manway opening 56 which is normally closed by a plate 58 attached to the drum by appropriate or suitable holding means.

Below drum cover 54 is a refractory body 60 for increasing the thermal protection of the lower part of the drum 30.

The gaseous reaction products from the combustion chamber 14 pass through the outlets 20 and 22 and then pass recurrently back and forth transversely of the banks of tubes 26 and 28 in the general directions indicated by the lines 62 and 64. The gases are caused to pass over the tubes in this manner by vertically spaced and horizontally extending baffles 70-79. The baffles 75

70, 72, 74, 75, 77, 79 extend radially inwardly from the shell to a position adjacent the inner rows of tubes of the associated banks of tubes 26 and 28, and the remaining baffles extend from the wall 36 outwardly on both sides thereof to the outermost rows of the banks of tubes. The baffles constitute means directing high temperature gases over the banks of tubes connecting the drum 24 with the drum 30.

A vapor, or steam under pressure, passes from the upper part of the drum 24 to the circular inlet header 80 of the superheater. This header may be formed by a number of arcuate sections such as 81-84 which are individually supplied with steam from the drum 24 by the tubular connections such as 91-94 (Fig. 3). These connections and the header constitute means connecting the superheater with the drum 24. Extending downwardly from each of the sections of the upper superheater header 80, are wall tubes such as the tubes 96-98. These tubes are held in position in substantial contact with the wall of the shell 10 by means such as that indicated in Figs. 7 and 8. This means includes a metallic sleeve 100 welded to the shell as indicated at 102. Slidably extending into the upper end of the sleeve 100 is the downwardly extending portion 104 of a right angle bent rod. The upper portion 106 of this rod is welded to the tube 96 as indicated at 108. A similar rod 108 is secured to the tube 98 and has its upwardly extending portion disposed within the lower part of the sleeve 100. It is to be understood that such securing devices are distributed throughout the length and width of the wall of superheater tubes which constitutes a lining for the shell 10.

In the higher temperature gas zones, and preferably up to the level of the baffles 72 and 77, the superheater tubes are fully studded, as indicated in Fig. 9. The faces of these tubes toward the interior of the shell, as well as the side faces of the tubes, have welded thereon studs such as those indicated at 110-114, and the shell lining is completed by a refractory material stratum such as 116 packed around the tubes and studs in a semi-plastic condition, as is well-known in the art. In a lower temperature zone the superheater tubes such as 96 and 98 are only partially studded, the faces of the tubes such as 120 and 122 presented toward the interior of the shell are not covered with the studs and refractory construction. The lower parts of some of the superheater tubes are bent around the gas ports 16 and 18 of the combustion chamber, and all of the superheater tubes extend below these ports to a connection with a lower superheater header 130. Superheated steam passes from the circular header 130 to an outlet header 132 which extends through an opening 134 in the base or support 136 for the shell 10. Connections between the headers 130 and 132 are indicated at 140-143.

In order that saturated steam or vapor may be conducted directly from the drum to one or more safety valves and to the superheater, the drum 24 has connected therewith a tubular outlet 150 which extends through an opening at the top of the shell 10 and is connected therewith by a pressure tight expansion joint construction such as 152. The tubular outlet 150, with or without the tubes 91 and the superheater and its connections, constitutes means connected with the vapor generating tubes and extending through the shell 10 to constitute an outlet for vapor un-

der pressure. The tubular outlet 150 also constitutes a safety valve conduit.

To provide for access to the interior of the drum 24, there is a manway construction 160 secured to the drum and aligned with another manway construction 162 which is secured to the shell 10 at the position indicated in Fig. 2.

170 constitutes a feed pipe connection extending through the shell at 172 and connected with the drum at 174 as means for the purpose of supplying the vapor generator with a liquid from which the vapor is to be generated.

From the above description, it will be noted that the shell of the pressure vessel acts as a column in which the steam generator is supported. The load of the pressure vessel and the steam generator is taken at the base of the installation upon support 136. This support may be conveniently shaped as a cylinder which is in direct compression.

The superheater wall tubes 98 are supported in direct compression from the header 130, this header being supported by the shell 10, as by inwardly extending brackets 180 similar to the upper brackets 32, secured to the shell. With this arrangement, there will be some degree of relative movement between the superheater inlet header 80 and the upper drum or header 24 for the steam generator. This movement is readily permitted without undesirable stress, by reason of the looped construction of the superheater supply tubes such as 91—94.

The support of the steam generator at a position near the brackets 34 permits the tubular feed water connections, and other connections such as the gauge glass conduits 57 and 59 to be brought out of the pressure vessel at a level coincident with the transverse axis of the upper drum 24. With this arrangement, there will be very slight relative movement between such connections and the shell of the pressure vessel. What little movement thereby will be readily taken up by the bent or looped construction of these connections.

While in accordance with the provisions of the statutes I have illustrated and described herein the best form of my invention now known to me, those skilled in the art will understand that changes may be made in the form of the apparatus disclosed without departing from the spirit of the invention covered by my claims, and that certain features of my invention may sometimes be used to advantage without a corresponding use of other features.

What is claimed is:

1. In fluid heat exchange apparatus, a metallic pressure vessel consisting of an upright cylindrical shell of large volume, a vapor generator including upper and lower drums and connecting banks of vapor generating tubes disposed as a unit within the shell and pendently supported from the upper part of the shell, a row of large diameter downcomer tubes disposed between said banks of tubes and directly connecting said upper and lower drums, a high pressure combustion chamber within the shell, baffles directing high temperature gases from the combustion chamber over said banks of tubes and to a gas outlet at the opposite part of the shell, tubular means through which the vapor generator is supplied with a liquid for circulation therethrough and the development of a vapor under pressure, a superheater including a row of closely spaced tubes disposed closely adjacent to and distributed in circular arrangement around the inner

surface of the shell, looped tubular means connecting the vapor space of the upper drum with the upper ends of the superheater tubes, and a superheater outlet header secured to the shell and connected with the lower ends of the superheater tubes.

2. In fluid heat exchange apparatus, a metallic pressure vessel forming an upright cylindrical shell of large volume, a vapor generator including upper and lower drums and connecting banks of vapor generating tubes disposed as a unit within the shell and pendently supported thereby, a row of spaced large diameter downcomers directly connecting said upper and lower drums, refractory means associated with the downcomer tubes to fill the spaces between them and complete a wall extending across the shell and separating the banks of tubes, means directing high temperature gases from one part of the shell over said banks of tubes and to a gas outlet at the opposite part of the shell, tubular means through which the vapor generator is supplied with a liquid for circulation therethrough and the development of a vapor under pressure, a superheater including a row of closely spaced tubes disposed closely adjacent to and distributed in circular arrangement around the inner surface of the shell, looped tubular means connecting the vapor space of the upper drum with the upper ends of the superheater tubes, and a header constituting a superheater outlet connected with the lower ends of the superheater tubes, said header being secured to the lower part of the pressure vessel to form a bottom support for the superheater.

3. In fluid heat exchange apparatus, a large diameter metallic pressure vessel adapted for the passage of high temperature and high pressure gases therethrough in normal operation, a heat absorbing unit heated by said high pressure gases including tubes vertically disposed within the pressure vessel, supporting means near the top of the pressure vessel for pendently supporting said heat absorbing unit, upper and lower drums included in said heat absorbing unit, the supporting means being connected to the upper drum, a feed water connection to the upper drum, a blow-down tubular connection extending from the lower drum and then through the upper drum and the wall of the pressure vessel to the atmosphere in the horizontal zone of said supporting means, a bottom supported superheater including upper and lower ring headers and a ring of upright wall tubes adjacent the wall of the pressure vessel, a safety valve conduit extending upwardly from the upper drum through the wall of the pressure vessel, looped superheater supply tubes in communication with the safety valve conduit and the upper header of the superheater to supply steam to the latter, and tubular means extending from the lower header of the superheater through the wall of the pressure vessel for the delivery of superheated steam.

4. In fluid heat exchange apparatus, a large diameter metallic pressure vessel providing an upright cylindrical shell adapted for the passage of high temperature and high pressure gases therethrough in normal operation, a heat absorbing unit heated by said high pressure gases including tubes vertically disposed within the pressure vessel, supporting means near the top of the pressure vessel for pendently supporting said heat absorbing unit, upper and lower headers or drums included in said heat absorbing

unit, a vaporizable liquid inlet connection to the upper drum or header, a blow-down tubular connection extending from the lower drum and then through the upper drum or header and through the wall of the pressure vessel to the atmosphere in the horizontal zone of said supporting means, a bottom supported superheater including upper and lower ring headers and a ring of upright wall tubes adjacent the wall of the pressure vessel, a safety valve conduit extending from the upper drum or header of said unit through the wall of the pressure vessel in said horizontal zone, bowed superheater supply tubes directly connecting the safety valve conduit and the upper header of the superheater, and tubular means extending from the lower header of the superheater through the wall of the pressure vessel for the delivery of superheated vapor.

5. In fluid heat exchange apparatus, an upright cylindrical pressure vessel forming a shell 20 of large volume, a ring of upright fluid conducting wall cooling tubes contiguously arranged relative to the inner surface of the shell and extending from a position near the bottom of the shell to a position near its top, a thick walled 25 refractory construction presenting a high temperature reaction chamber within said ring of tubes and disposed at the lower part of the shell, the upper part of the reaction chamber having openings for the upward exit of high temperature gaseous reaction products, separated groups of horizontally spaced upright vapor generating tubes disposed within the shell above the reaction chamber, pressure parts constituting upper and lower fluid chambers which are connected by the vapor generating tubes, means other than said vapor generating tubes connecting said upper and lower chambers, baffle means causing the reaction products to pass over the groups of tubes in a plurality of transverse gas passes,

means forming an exit passage for the reaction products near the top of the shell, refractory baffle means associated with the downcomers and separating said groups of tubes, means connecting the ring of tubes to the fluid system of the vapor generating tubes, said last named means including upper header means and bent tubular connections communicating with the upper header means, lower header means at the lower ends of said ring of tubes and connected thereto, means secured to the shell for affording bottom support for the lower header means and said ring of tubes, and means secured to the upper part of the shell for pendently supporting the groups of vapor generating tubes.
